UNITED STATES PATENT OFFICE

93,250

DESIGN FOR A RANGE

Arthur Stockstrom and Almer H. Brodbeck, St. Louis, Mo., assignors to American Stove Company, St. Louis, Mo., a corporation of New Jersey

Application May 31, 1934, Serial No. 51,983

Term of patent 14 years

To all whom it may concern:

Be it known that we, ARTHUR STOCKSTROM and ALMER H. BRODBECK, citizens of the United States, residing at St. Louis, and State of Missouri, have invented a new, original, and ornamental Design for Ranges, of which the following is a specification, reference being had therein to the accompanying drawing.

The accompanying drawing is a perspective view of a range, showing our design.

The predominating features of our new design for ranges comprise an open supporting framework carrying centrally arranged roasting and broiling compartments, each provided with separate doors which together extend substantially from the lower portion of said supporting frame,

the roasting oven having a closed top, and burner compartments located at opposite sides of the said central portion, each burner portion having located below it a compartment extending downwardly, the said burner compartments extending upwardly to substantially a horizontal plane with the top of the said central portion, and a vertically arranged panel extending upward from the rear edges of said compartments.

We claim:

The ornamental design for a range as shown and described.

In testimony whereof, we hereto affix our signatures.

ARTHUR STOCKSTROM.
ALMER H. BRODBECK.
